CARD WITH GARMENT ATTACHING PORTION

Frank J. Allen, Jr., Doraville, Ga.

Application August 29, 1958, Serial No. 758,154

6 Claims. (Cl. 40—1.5)

This invention relates to a card with garment attaching portion and especially to those cards or tags or badges usually worn on the person and either clamped thereon or fitted into the lapel, the shirt, or other garment opening by means of a portion of the device formed into an attaching arrangement.

There are many uses and demands for cards, badges and tags to be worn on the person in such instances as when attending a convention to have one's name displayed or when holding an open house for business affairs or when having a special sale at a store at which time the sales people wear advertising cards. The usual arrangement for convention cards consists of a plastic cover with a special spring pin on the back punctured into the clothing. Other known arrangements utilize such things as bendable tabs, screw clamps and the like. A demand exists for a card that has the attaching arrangement formed from the card itself and which can be used in the ordinary lapel slot or in some other button hole on the person.

The present device presents a card which has a particular attachment portion for insertion in the lapel slot. Generally described, without the use of patent terminology and without limitation on the scope thereof, this invention consists of a flat sheet of material in any desired geometrical or ornamental shape and can be folded into three dimensional shapes if desired. Formed preferably by die cutting the sheet, at the top edge thereof is an attachment portion consisting of a neck portion connected with said sheet extending to form an elongated tab inclined with the normal vertical axis of the card itself. The tab at its upper end extends and bends to form a depending arcuate hook-like protrusion and at the bottom extends to form an arcuate tip. The overall length of the tab is preferably longer than that of the conventional lapel slots or buttonholes. In the operation of the device, it is necessary to incline or tilt the hook-like protrusion to insert and hook it into the lapel hole and behind the lapel and then merely rotate the card counter-clockwise to bring the hook end downwardly and then slipping the lower tip through the hole thereby placing the entire attachment portion into and through the lapel hole with the neck of the portion extending through the hole to the outside and with the card itself hanging neatly and in alignment from the front of the coat. If desired, the device can be pinned to the garment when no opening exists.

One primary feature of my invention is to provide an attachment portion formed on a card for attaching and holding the card in a conventional lapel opening or buttonhole, and which can be pinned to the garment if necessary.

Another feature resides in the inclined formation of the protrusion and in the hook-like upper end which is inserted and hooked in the lapel opening to maintain the card therein in aligned condition.

An additional feature resides in the formation of the

2

attaching tab wherein it is concealed completely after insertion.

Still another advantage is found in the construction of the tab whereby it is readily die punched or cut at the same time the cards are formed into their desired shapes from a large sheet of material.

There are other advantages and objects of this invention and these will become apparent to those skilled in the art upon reading the following specification taken in conjunction with the accompanying drawings, in which:

Fig. 1 is a front elevation of a card made in accordance with this invention inserted in and hanging from the opening in a lapel.

Fig. 2 is a plan view of a card substantially like the one shown in Fig. 1.

Fig. 3 is a plan view of another card formed into the ornamental shape of a shoe and employing the attachment member of this invention pinned on a garment.

Fig. 4 is another embodiment of my invention employing the same attachment member confined within the body of the card.

Fig. 5 is still another embodiment of this invention wherein the attachment portion has been bent behind the card so that the card completely covers the entire attachment portion and lapel hole.

Referring initially to the card in Fig. 2, it is seen that the card 10 consists of a flat, thin sheet body 12, of cardboard or the like, that may be printed with identification, advertising matter or ornamental material and which is formed at the top 14 thereof with an attaching device, designated generally at 16 with a neck portion 18 connecting it with the main sheet body 12 and extending at an inclined angle to the normally vertical axis of the sheet 12 to form an elongated attaching member 20. Attaching member 20 is slightly enlarged at its top 22 and bends thereat to form a hook-like end 24 with a curved point 26 extending to form an arcuate indentation 28 with body 12. The other end 30 of the attachment member 20 terminates in a curved tip 32 forming an arcuate indentation 34 with the main sheet body 12. It is desirable that the overall length of attaching member 20 be greater than the length of the usual lapel opening.

The card 36 in Fig. 1 is rectangular and substantially the same as the card 10 in Fig. 2 and is made in accordance with the attachment device 20 therein. Card 36 has the attachment portion 20 inserted in a conventional man's suit lapel 38 through the usual lapel hole 40. This insertion was done simply and easily by inclining or tilting the card clockwise from its present position to where the end 24 is inserted through the hole 40 first. Then the card is rotated counter-clockwise back to its present position in Fig. 1 and raised slightly in the hole 40 to insert the tip 32. After the card 36 is released, it assumes and maintains the position shown in Fig. 1 with attachment member 20 behind the lapel 38 jostled and while it will jiggle when jostled it will assume normal aligned condition when permitted to hang still, without becoming detached.

The modified form 44 in Fig. 3 has the same attachment portion 20 and respective parts such as end 24 and tip 32 as in the other embodiments but for illustrative purposes has been formed with the card portion die-cut into the shape of a shoe 46 with a surface 48 on which information may be printed. This sort of design can be used at store sales to call attention to some special thing. In this embodiment, the attachment portion 20 is attached to a garment 50, such as a lady's dress, by means of the conventional straight pin 52. This would be used for those people in the store or where ever the device is being worn who do not have lapels or shirt buttonholes.

The modified card form 56 in Fig. 4 is very similar to

the card 10 in Fig. 2, except that the attachment portion 20 has not been outlined in profile and cut away from the top 57 of the top of the card 56 and the sheet 58 continues to surround the entire attachment portion 20. The entire attachment portion 20 has been through cut along lines through the sheet 58 to form the parts of attachment portion 20 which remains connected with the card by the neck 18. It is necessary to bend the attachment portion 20 slightly from the plane of the sheet 58 in order to insert it through the hole in the lapel. The insertion is the same as in the other embodiments and the difference is in the stability since the upper part 57 of the card will extend and press against the lapel, and show outside.

The card 62 in Fig. 5 is made from the card 10 as shown in Fig. 2. Card 62 is modified to conceal the attachment portion 20. Card 10 is bent transversely upon itself at the top 14 thereof down a distance to form line 63 on card 62 at the bottom thereof with a portion 66 bent against the front. Then the card is inverted and the portion 66 thereof is laid flat against the back of the front sheet portion 68 and glued thereto, except that the attachment portion 20 is left free of glue down to the neck area 18 to form the hinge folding line 70. In the operation of the device 62, the attachment portion is inserted in identical manner as those other embodiments shown herein by bending the attachment portion 20 away slightly from the plane of the front sheet portion 68 and back sheet portion 66 about line 70 and inserted in the lapel hole. When positioned in the lapel, neither the neck 18 or any of the attachment portion 20 is visible from the front of the card 62.

While I have shown and described my invention in detail and presented several embodiments thereof, this is not in any way a limitation on the scope thereof since various alterations, modifications, substitutions, eliminations, changes and departures may be made in the devices shown herein without avoiding the scope of this invention as defined in the appended claims.

I claim:

1. In a card for attachment on a garment to be worn by a person, a flat sheet card body portion having a flat surface thereon on which advertising matter and other indicia may be affixed as by printing, said card body portion extending at the upper end thereof to form an attaching member formed integrally with said card from said sheet material, said attaching member being elongated in formation and being attached to said sheet body intermediate its length in disposition inclined to the normal vertical axis of the sheet body, one end of said attaching member being formed in an arcuate shape bending to form a hook-like member, the other end of said attaching member being arcuate to form an arcuate tip, said device being inserted by rotating same until said hook-like end will enter said opening first and thereafter inserting same through said opening and then rotating said device in the other direction to insert said tip therein, said entire attaching member then lying behind said material into which said device is inserted to hold said card therein.

2. In a card constructed from a flat sheet of material for attachment on a garment to be worn by a person, a flat sheet card body portion having a flat surface thereon on which advertising matter and other indicia may be affixed as by printing, said card body portion extending at the upper end thereof to form an attaching member formed integrally with said card from said sheet material, said attaching member being elongated in formation and being attached to said sheet body intermediate its length in disposition inclined to the normal vertical axis of the sheet body, one end of said attaching member being arcuately shaped to form an end member with an indentation thereunder with the sheet body, the other end of said attaching member being arcuate to form an arcuate tip extending to form a recessed portion with

said sheet body, said device being inserted by rotating same until one end will enter said opening first and thereafter inserting same through said opening and then rotating said device in the other direction to insert said other end therein, said entire attaching member then lying behind said material into which said device is inserted to hold said card therein.

3. In a card for attachment on a garment to be worn by a person, a flat sheet card body portion having a flat surface thereon on which advertising matter and other indicia may be affixed as by printing, said card body portion extending at the upper end thereof to form an attaching member formed integrally with said card from said sheet material, said attaching member being elongated

15 in formation and being attached to said sheet body intermediate its length in disposition inclined to the normal vertical axis of the sheet body, one end of said attaching member being formed in an arcuate shape bending to form an end member spaced by a recessed portion from

20 said body, the other end of said attaching member being arcuate to form an arcuate end indented from said sheet body, said recessed portion and said indentation forming a thin neck attaching said attaching member on said sheet body, said device being inserted by rotating same until

25 one end will enter said opening first and thereafter inserting same through said opening and then rotating said device in the other direction to insert said other end therein, said entire attaching member then lying behind said material into which said device is inserted to hold

30 said card therein.

4. In a card constructed from a flat sheet of material for attachment on a garment to be worn by a person, a flat sheet card body portion having a flat surface thereon on which advertising matter and other indicia may be affixed as by printing, said card body portion extending at the upper end thereof to form an attaching member formed integrally with said card from said sheet material, said attaching member being elongated in formation and being attached to said sheet body intermediate its length

40 in disposition inclined to the normal vertical axis of the sheet body, one end of said attaching member being formed in an arcuate shape bending to form a hook-like member with an indentation thereunder with the sheet body, the other end of said attaching member being

45 arcuate to form an arcuate tip extending to form a recessed portion with said sheet body, both of said recessed portions defining a connecting neck where said attaching member joins said body, the overall length of said attaching member at its longest straight line point being

50 longer than the length of the usual buttonhole or lapel hole whereby said device is prevented from being inserted in alignment, said device being inserted by rotating same until said hook-like end will enter said opening first and thereafter inserting same through said opening

55 and then rotating said device in the other direction to

insert said tip therein, said entire attaching member then lying behind said material into which said device is inserted to hold said card therein.

5. The device in claim 4 wherein said sheet body is discontinuous about all of said attaching member, there being only the neck portion connecting said members together.

6. The device in claim 4 wherein card is inverted and said top of said card is bent to form a bottom fold line to fold said card upon itself with one portion thereof against said sheet body, said attaching member thereby being behind said sheet body, said overlying portions being attached with said attaching member free to bend about said neck line.
